- [54] HOUSING FOR A CIRCUIT BREAKER
[75] Inventor: Albert D. Lisnay, Sarasota, Fla.
[73] Assignee: Heinemann Electric Company, Trenton, N.J.
[**] Term: 14 Years
[21] Appl. No.: 651,216
[22] Filed: Jan. 21, 1976

1972, p. 1672, Housing for Adapting Panel Connector for Cable.

Primary Examiner—Wallace R. Burke
Assistant Examiner—Catherine Kemper
Attorney, Agent, or Firm—Joseph G. Denny

[57] CLAIM

The ornamental design for housing for a circuit breaker, as shown and described.

DESCRIPTION

FIG. 1 is a front perspective view of a housing for a circuit breaker showing my new design, the cap being in the depressed position;

FIG. 2 is a rear perspective view thereof, the cap being illustrated in the raised position;

FIG. 3 is a front perspective view thereof, the cap being illustrated in the raised position;

FIG. 4 is a bottom plan view thereof;

FIG. 5 is a top plan view thereof;

FIG. 6 is a front perspective view of a second embodiment of my design;

FIG. 7 is a rear perspective view thereof;

FIG. 8 is a bottom plan view thereof;

FIG. 9 is a top plan view thereof.
The characteristic feature of my design resides in the elongated housing, as shown.
